WILLIAM J. BURKE AND HENRY G. CLAUSING, OF PORTSMOUTH, OHIO.

MACHINE FOR FINISHING THE TOE AND INSOLE OF LASTS.

Application filed January 10, 1923. Serial No. 611,835.

To all whom it may concern:

Be it known that we, WILLIAM J. BURKE and HENRY G. CLAUSING, citizens of the United States, and residents of the city of Portsmouth, county of Scioto, and State of Ohio, have invented certain new and useful Improvements in Machines for Finishing the Toe and Insole of Lasts, of which the following is a specification.

Our invention relates to an improvement in machines for finishing lasts, and an object thereof is the provision of an improved machine for finishing the toe and insole of lasts particularly lasts of the hinged type, where-
15 in the last and a model are held in chucks or holders, the chuck engaging the last be-
tween the breaking point of the last and the toe, and in such a way as to enable the toe and insole to be finished without changing
20 the position of the last in the chuck during the finishing operation.

It will be appreciated by those skilled in this art that a machine of the type above referred to is of material advantage in the finishing of lasts as compared with the usual type of last finishing machine, particularly when finishing hinged lasts, in view of the fact that in the present machine the last is chucked between the hinge and toe whereas prior last finishing machines chuck the last at the toe and heel. In the former case the last is held rigidly in place, while in the latter there is always more or less yield or give to the last owing to the hinge or joint.

Referring to the accompanying drawings,

Fig. 1 shows an embodiment of our invention in plan;

Fig. 2 is a section taken substantially on the line 2—2 of Fig. 1;

Fig. 3 is a section of the improved chuck shown in Fig. 2, the section being taken substantially on the line 3—3 of Fig. 1;

Figs. 4 and 5 are modified forms of holding devices for holding the last and model in position on the chuck.

Referring to the drawings in detail,—1 designates a chuck-supporting rod which is suspended from hangers (not shown) to permit of the rod being oscillated.

On the chuck-supporting rod we mount a chuck 2 provided for the purpose of holding a last to be finished and a model last to be duplicated.

The chuck comprises a bed plate 3 adapted

to be rotated or oscillated upon the rod 1 and also to be moved axially thereof. The bed plate is bifurcated at its front end to provide projections 4 and 5 each of which carries a vertically extending pin 6 project-
60 ing upwardly from the face of the projec-
tions, these pins providing a support for the toe of the last to be finished and for the toe of the model, the pins engaging the under side of both the last and model.

Slidably mounted on the bed plate 3 is a plate 7 adapted to be moved endwise with respect to the bed plate, this plate also being bifurcated to provide extensions 8 and 9 corresponding to the projections 4 and 5 above referred to. The extension 8 carries a pair of pins 10 and 11 extending upwardly from the face thereof while the projection 9 carries a pair of similar pins 12 and 13. The pins 10 and 11 are adapted to engage the under side of and to support a last to be finished while the pins 12 and 13 are adapted to similarly engage and support the model last. By sliding the plate 7 relatively to the bed plate 3 carrying with it the pins 10, 11 and 12, 13 the machine can be accommodated to lasts of any size.

The projection 4 of the plate 7 is provided with a screw-threaded rod 14 and the projection 5 is provided with a similar rod 15 each of these rods being provided with a wood screw-thread to enable them to be screwed into the bottom of the last and model. The rods 14 and 15 are preferably positioned centrally with respect to the pins 6, 10, 11 and 6, 12, 13 to ensure that the last and model will be pulled or drawn down evenly upon and held fixedly against the supporting pins.

In operation the bottoms of the last to be finished and the model are spotted to accord with the location of the pins 6, 10 and 11 and 6, 12 and 13 relative to the toe and one insole line. The last and model are then placed in position upon these pins and the rods 14 and 15 screwed into the bottoms of the last and model to draw the same firmly upon their respective pins. The chuck is then manipulated to bring the toe and insole of the model into engagement with a guide wheel 17 and to at the same bring the last into engagement with the cutter 16 to enable the last to be cut away to exactly duplicate the model.

It will be seen that supporting pins for

the last and model as well as the rods 14 and 15 all engage the last and model on the under side which permits the finishing of both the toe and insole of the last and as previously pointed out by merely sliding the plate 7 with respect to the bed plate 3 the chuck will accommodate lasts of various sizes.

It will be seen also that the last is held by the toe only, that is the chuck engages only that portion of the last lying in front of the hinge so that, as above pointed out, the last is necessarily held rigidly throughout the finishing operation.

In Fig. 4 we have modified the construction of the rods 14 and 15 by which the last to be finished and the model last are drawn down in place upon their respective supporting pins. From this figure it will be seen that we provide pins 18 which project through the face of the projections 4 and 5 of the bed plate 3 these pins at their upper ends being provided with an offset 19 adapted to engage the walls of an opening 20 in the under side of the last to be finished and the model last. The pins are held against longitudinal movement in the bed plate 3 by the members 21 and 22. When the last to be finished and the model last are placed in position upon the chuck the pins 18 will enter the openings 20 in the last and model and may then be given a partial rotation to bring the offset 19 into firm engagement with the wall of the opening 20 so as to hold the last and model against movement on their supporting pins.

In Fig. 5 we have provided another modification of the pins 14 and 15. In this form of our invention the bed plate 3 is provided with upwardly projecting pins 23 corresponding to the pins 14 and 15 of Fig. 1 and the last to be finished and the model last are each provided with a split bushing 24 the peripheries of which are provided with projections 25 or their equivalent so as to hold the bushings in place in the last and model. When the last and model are placed in position in the chuck the rods 23 are screwed into the bushings 24 to draw the last and model firmly down upon their respective supporting pins the bushings ex-

panding under this operation so as to not be drawn out of the last and model.

We claim:

1. In combination a chuck, a support carried thereby for supporting a last block on the chuck, adjustable supports, said adjustable supports being adjustable relative to the first mentioned support to adapt the chuck for last blocks of different sizes, and a securing member adapted to engage the underside of the last to hold the same in place upon said supports.

2. In a machine for finishing lasts, a rod, a bed plate slidably mounted thereon, a last support carried by said bed plate, a plate slidably mounted on said bed plate, last supports carried thereby, and a screw carried by said bed plate and adapted to draw a last into rigid engagement with said last supports.

3. In a last finishing machine, a chuck for holding a last to be finished, said chuck comprising a bed plate, a last support mounted on and extending upwardly from the forward end of said bed plate, a plate adjustably mounted upon said bed plate, a pair of last supports mounted on and extending upwardly from the face of the last-mentioned plate and a screw carried by said bed plate and held against axial movement therein, said screw being adapted to screw into the bottom of the last to be finished to draw the same into rigid engagement with said last supports.

4. In a machine for finishing the toe and insole of a last, a chuck for holding a last to be finished, supporting pins carried by said chuck and upon which a last to be finished is supported one of said pins being adjustable to vary the distance between the pins, and a rod carried by said chuck to be screwed into the last to draw the same firmly into engagement with the supporting pins, said pins and rod engaging the last on the under side thereof to permit the toe and insole to be finished without resetting the last in said chuck.

This specification signed this 30 day of Dec., 1922.

WILLIAM J. BURKE.
HENRY G. CLAUSING.
